RADIO AERIAL APPLIANCE

Charles T. Oberle, Somers Point, N. J.

Application May 7, 1941, Serial No. 392,364

3 Claims. (Cl. 250—16)

This invention relates to new and useful improvements in appliances for radios of any type and more particularly to the type having a built-in antenna which is usually directional in reception, the principal object of the present invention being to provide a combination structure including an antenna which can be mounted adjacent to but externally of the receiver in a manner that will alleviate directional limitations of the built-in antenna type of receiver.

Another important object of the invention is to provide an appliance for radio receivers which encompasses not only an antenna but also a program holder, the latter serving to conceal the antenna.

These and other objects and advantages of the invention will become apparent to the reader of the following specification.

In the drawings—

Figure 1 is a front elevational view of a receiver showing the appliance in upright position.

Figure 2 is a rear elevational view of a receiver showing the appliance in elevated position and by dotted lines in lowered position.

Figure 3 is a front elevational view of the appliance without its pivoting attachment.

Figure 4 is a rear elevational view with the back wall broken away and showing a hanger element indicating that this form of the invention is especially adapted for disposition on a wall.

Figure 5 is a cross sectional view taken substantially on the line 5—5 of Figure 4.

Referring to the drawings wherein like numerals designate like parts, it can be seen in Fig. 1 that numeral 5 generally refers to a conventional receiver of the type having a built-in antenna.

The present invention is generally referred to by numeral 6 and consists of a combination radio program and antenna holder. This holder consists of a rectangular-shaped frame 7 which may be slotted at its top to permit the insertion of the various elements of the holder so that the edge portions thereof will seat in internal grooves 8 of the frame 7. These elements consist of a pair of wall members 9 and 10 which can be of cardboard or some other suitable insulation material between which a web or meshed form of antenna 11 is interposed, this antenna having a lead wire 11a extending therefrom. A properly marked off program sheet 12 is disposed at the front side of the frame and against the front

wall 10 in the manner substantially shown in Figure 5.

The drawings show two forms of the invention, the form shown in Figures 1 and 2 requires a clamp 13 having a set screw 14 which is driven against one side wall of the radio receiver at the back edge thereof and this clamp 13 has an inwardly disposed bracket member 15 from which a pin 16 projects rearwardly. This pin is disposed snugly in a barrel 17 carried by a V-shaped bracket 18 secured to one lower corner of the frame 7. Obviously, the friction between the pin 16 and the barrel 17 will be sufficient to hold the frame 7 in the upright position shown in Figure 2 or in the lower position shown by dotted lines in Figure 2.

It is preferable that the appliance 6 be retailed with the swingable handle member 19 attached to the back wall 9 so that it will be optional with the buyer to either buy the necessary clamp 13 if he wants the appliance 6 on the radio receiver or else dispense with the clamp and the bracket 18 and simply hang the appliance on a wall hook by the hanger 19.

While the foregoing specification sets forth the invention in specific terms, it is to be understood that numerous changes in the shape, size and materials may be resorted to without departing from the spirit and scope of the invention as claimed hereinafter.

Having described the invention, what is claimed as new is:

1. A combination structure comprising a frame, an antenna structure spanning the inside of the frame, and a program sheet disposed in the frame and forming a concealing front for the antenna structure.

2. A combination structure comprising a frame, an antenna structure spanning the inside of the frame, a program sheet disposed in the frame and forming a concealing front for the antenna structure, and a stiff back wall for the antenna structure.

3. A combination structure comprising a frame, an antenna structure spanning the inside of the frame, a program sheet disposed in the frame at the front of the antenna structure, and a stiff wall at each side of the antenna structure, one wall forming a backing for the antenna structure and the other wall a plane surface backing for the program sheet.

CHARLES T. OBERLE.
